UNITED STATES PATENT OFFICE.

PHILANCY D. MORTON, OF LEMOYNE, OHIO.

SPOOL-HOLDING FRAME.

SPECIFICATION forming part of Letters Patent No. 691,287, dated January 14, 1902.

Application filed January 31, 1900. Serial No. 3,475. (No model.)

To all whom it may concern:

Be it known that I, PHILANCY D. MORTON, a citizen of the United States, residing at Lemoyne, in the county of Wood and State of Ohio, have invented a new and useful Spool-Holding Frame, of which the following is a specification.

My invention relates to improvements in spool-holding frames for looms; and the main object in view is to provide an improved drawing-frame capable of being easily and quickly supplied with spools, bobbins, quills, or tubes containing the warp.

With these ends in view the invention consists in the novel combination of devices and in the construction and arrangement of parts, as will be hereinafter fully described and claimed.

In the drawings, Figure 1 is a top plan view of a spool-holding frame embodying the features of the invention. Fig. 2 is a longitudinal sectional elevation through the complete apparatus which embraces said spool-holding frame. Fig. 3 is a detail side elevation of one of the warp-frames equipped with two series of spools.

The same numerals of reference are used to indicate like and corresponding parts in each of the several figures of the drawings.

The spool-holding frame of my apparatus is adapted to be arranged adjacent to a carpet-weaving loom. This spool-holding frame consists of upright main frames 10 and 11 and a head-frame 12, said upright main frames adapted to sustain a plurality of warp-frames, which carry the spools or equivalent devices containing the warp-threads, while the head-frame serves as the support for certain of the lease-formers adapted to properly direct the warp-threads from the entire number of bobbins, which are supported by the warp-frames, on the two main frames 10 11. Each main frame has a series of cross-rails 13 connecting the sides of the frames together, one of the cross-rails 13^a having an inclined or beveled upper edge 14. The head-frame 12 has its side pieces joined at 15 to the upper ends of the main frames 10 11, and said side pieces of the head-frame are united firmly together by a warp-support 16, the upper edge of which is

rounded, as at 17, to facilitate the passage of the warp-threads thereover. As shown by the drawings, I prefer to incline the main frames 10 11 to each other, so that they will converge at their upper ends, and this arrangement enables the side pieces of the head-frame to be fastened to the upper ends of both main frames. The main frame 11 carries or supports a series of rear warp-frames 18, converged toward their lower extremities for convenience in feeding the warp and each having a pair of side rails connected by a series of short cross-bars 19, the upper cross-bar 19^a being provided with a beveled under edge 20. The series of warp-frames 18 are applied against the rear side of the frame 11, so that the cross-bars of the warp-frame will rest upon the cross-bars of the main frame, thus bringing the rail 19^a of the warp-frame in position for its beveled under surface to have interlocking engagement with the beveled top edge of the cross-rail 13^a of the frame 11, whereby each warp-frame is confined on the frame 11 to be held thereby against accidental displacement. The rear warp-frame 18 has a series of spindles 21 projecting outwardly therefrom, said spindles being attached, preferably, to the side rails of each warp-frame. Another series of warp-frames 22 are applied to the main frame 10, and to distinguish the warp-frames 22 from the similar frames 18 I will hereinafter refer to said frames 22 as the "front" warp-frames. The side rails of each front warp-frame are joined by a series of cross-bars 23, the upper rail or bar of which series is indicated by 23^a as having a beveled or inclined lower edge 24. The series of front warp-frames 22 are applied laterally against the cross-rails of the main frame 10, so that the cross-bars 23 23^a may rest upon the cross-rails 13 13^a for the beveled edges of the bars 23^a to interlock with the corresponding edge of the upper cross-rail on the main frame 10. Each front warp-frame has a series of spindles 25 fastened to the side bars thereof and projecting outwardly therefrom. It is to be observed that the warp-frames 18 22 are applied to opposite sides of the main frames, so as to partake of the inclination thereof, and the spindles on the two series of warp-frames 100

are adapted to receive the spools 26 or the mechanical equivalents for such spools, said equivalent devices being in the form of bobbins, quills, or tubes.

5 In the head-frame 12, substantially in alignment with the two series of warp-frames which are applied removably to the main frames, are supported lease-formers adapted to direct or guide the warp-threads from the number 10 of bobbins to and over the warp 16 on said head-frame. The lease-former for the warp-threads from the spools on the rear-frames 18 consist of a pair of slats 27 27, which are arranged parallel to each other to extend entirely across the head-frame, the ends of said slats being confined loosely in substantially vertical slots 28, which are formed in the side pieces of the head-frame. The lease-former for the warp-threads drawn from 20 the spools on the front warp-frames 22 consists of a pair of slats 29, the same being arranged parallel to each other and extending across the head-frame and the series of front warp-frames. These lease-formers are confined loosely in the slots 30, which are formed in the side pieces of the head-frame. The lease-formers for the front and rear warp-frames are supported in the head-frame, near the front and rear edges thereof, respectively, 25 so that the warp-support 16 lies in a vertical plane between said front and rear lease-formers, and the lease-formers and the warp-frames are thus arranged for service in connection with a single warp-beam, whereby all 30 of the threads from all the bobbins or spools on the two series of front and rear warp-frames are guided or directed over a single warp-support on the spool-holding frame. It is to be understood that the warp-threads on the 35 spools may be of different colors, so that the threads may be grouped or assembled as they are led from the spools through the lease-formers and over the warp-support to give stripes of different colors to the carpet fabric. 40

45 An adjustable overhanging frame 32 projects in an inclined direction from the head-frame 12 over the front series of warp-frames, and the side pieces of this adjustable frame are joined together at their outer front ends 50 by means of a roller 33. The side pieces of this overhanging frame are connected pivotally at 32^a to the side pieces of the head-frame 12, and said overhanging frame is adjustably supported in order to raise or lower the warp-threads by the braces 34, said braces having their free ends fitted in notches 35, provided in the lower edges of the side pieces forming the overhanging frame, said braces being attached to the main frame 10 and adjustable 55 within certain limits for supporting the overhanging frame in variable positions relative to the spool-holding frame. This overhanging frame carries or supports a lease-former between the warp-support 16 and the warp-60 roller 33, said lease-former consisting of the

pair of slats 36, which are loosely confined at their ends in the slots 37, the latter being formed in the side pieces of the overhanging frame.

The warp-threads are first drawn from the upper spools on the rear warp-frames and are threaded through the rear lease-former 27, over the warp-support 16, the lease-former 36, and the roller 33 of the overhanging frame, and thence to the warp-beam. The warp-threads 75 are drawn from the remaining spools on the rear warp-frames in order from top to bottom. The threads from the spools on the front warp-frames 22 are threaded through the front lease-former 29, carried over the warp-support 16, threaded through the lease-formers 36, and carried over the roller 33 to the warp-beam. The construction of the lease-formers enables the warp-threads to be passed freely therethrough, and the threads are crossed in 80 passing them around the warp-roller and through the lease-formers, so that the desired tension is obtained thereon. It is evident that one or all of the warp-frames may be removed from the drawing-frame to facilitate the operation of placing the filled spools on the spindles, but this is optional.

Changes within the scope of the appended claims may be made in the form and proportion of some of the parts, while their essential features are retained and the spirit of the invention is embodied.

Having thus described the invention, what I claim is—

1. In an apparatus for the purpose set forth, 100 a spool-holding frame having upwardly and inwardly inclined oppositely-disposed sides, a plurality of warp-frames mounted on said sides, each warp-frame having a pair of side rails which converge toward one end of said frame and carrying a plurality of spindles arranged in alignment thereon, the rails being held in fixed relation to each other, a warp-support above said warp-frames and in a vertical plane between the same, front and rear 105 lease-formers between the warp-frames and the warp-support, an adjustable frame connected to the spool-holding frame and projecting forwardly therefrom, and a lease-former supported by the adjustable frame. 110

2. In an apparatus for the purpose set forth, 115 a spool-holding frame provided with two series of warp-frames arranged in reversely-inclined positions, and having downwardly-converged side rails, a warp-support above said frames and in a vertical plane between the same, front and rear lease-formers between the warp-frames and the warp-support, an adjustable frame connected to the spool-holding frame and projecting forwardly therefrom, 120 and a lease-former supported by the adjustable frame, substantially as described.

3. In an apparatus for the purpose set forth, 125 a spool-holding frame provided with warp-frames, a warp-support, lease-formers on said 130

spool-holding frame between the warp-support and the warp-frames, an adjustable frame projecting from the spool-holding frame, a lease-former in said adjustable frame, and a 5 roller supported by the adjustable frame beyond the lease-former thereon, substantially as described.

In testimony that I claim the foregoing as my own I have hereto affixed my signature in the presence of two witnesses.

PHILANCY D. MORTON.
